CLAIM

The ornamental design for a mirror shoe storage cabinet, as shown and described.

DESCRIPTION

FIG. 1 is a bottom, front, right side perspective view of a mirror shoe storage cabinet, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an alternative perspective view of mirror shoe storage cabinet with its door opened;

FIG. 10 is an enlarged view of the portion labeled "10" framed in FIG. 9;

FIG. 11 is an enlarged view of the portion labeled "11" framed in FIG. 1; and,

FIG. 12 is an enlarged view of the portion labeled "12" framed in FIG. 8.

The small evenly spaced dashed broken lines in the drawings illustrate portions of the mirror shoe storage cabinet that form no part of the claimed design. The dash dot broken lines encircling portions of the mirror shoe storage cabinet in FIGS. 1, 8, 9 and illustrated in enlarged view in FIGS. 10, 11, 12 form no part of the claimed design.

1 Claim, 12 Drawing Sheets
